DESIGN FOR A COMBINED ROTARY BLOTTER AND PENHOLDER

Lorenz Grünzweig, Kew Gardens, N. Y.

Application December 3, 1938, Serial No. 81,537

Term of patent 7 years

To all whom it may concern:

Be it known that I, Lorenz Grünzweig, a citizen of the German Reich, residing at Kew Gardens, Long Island, in the county of Queens and State of New York, have invented a new, original, and ornamental Design for a Combined Rotary Blotters and Penholder, of which the following is a specification, reference being had to the accompanying drawing, forming part thereof.

In the drawing

Fig. 1 is a side view of the combined rotary blotter and penholder showing my new design;

Figure 2 is a rear view of the combined rotary blotter and penholder showing my new design;

I claim:

The ornamental design for a combined rotary blotter and penholder, as shown.

LORENZ GRÜNZWEIG,
